RICHARD C. LEAKE AND CHARLES F. ESTWICK, OF ROCHESTER, NEW YORK, ASSIGNEES
TO GENERAL RAILWAY SIGNAL COMPANY, OF ROCHESTER, NEW YORK.

TRAIN CONTROL.

Application filed September 21, 1923. Serial No. 664,045.

This invention relates to automatic train control systems of the continuous alternating current inductive type, and more particularly to means for tuning the various circuits of the car-carried apparatus so that this apparatus will respond substantially to the same degree for various frequencies within a certain range.

Generally speaking, in the type of system to which the present invention relates alternating current is transmitted through one or more suitable trackway circuits which inductively influence suitable amplifying apparatus on the train for maintaining a relay energized in accordance with the flow of such current. More specifically, one particular type of train control system of this general character includes a receiving element located in front of the first axle of the train which is in inductive relation with the rails of the trackway and responds to the flow of current in one direction in one of the rails, and in the other direction in the other rail corresponding to the usual track circuit current and conveniently called the loop circuit current; and another receiving element in inductive relation with the track rails and constructed to respond to the flow of current in the same direction in the two rails in multiple, conveniently called the simplex circuit current. On account of the limited current which may be applied in practice to the usual trackway circuit, and on account of the difficulty of inductively detecting such a small track circuit current through an intervening air gap, it is found desirable to tune the windings of the inductive influence receiving elements, to a certain degree at least, in order to be able to maintain the relay energized by the use of ordinary amplifying apparatus. In practice, the current in the track rails is derived from a transmission line supplied from commercial apparatus; and the frequency varies slightly. Consequently, if the receiving elements have their windings tuned sharply to resonate at the frequency of the signaling current, it is found that such slight variations in the frequency of this current causes a tremendous change in the efficiency of the influence receiving apparatus.

With the above and other considerations in mind, it is proposed in accordance with the present invention to provide a series or chain of circuits and devices between the

track or loop circuit influence receiving element and one element of a two-element car-carried relay, in which the winding of the receiving element is tuned to a frequency higher than the frequency of the proposed signaling current; and to provide a suitable series or chain of circuits and devices between the other or simplex receiving element and the other element of the relay, in which the winding of the simplex receiving element is resonant to a frequency lower than the proposed signaling frequency, so that two overlapped resonance characteristics are obtained in the detecting and amplifying apparatus for energizing the polyphase relay, which, due to this tuning, causes the efficiency to be much improved and to be substantially constant throughout a predetermined range of frequencies.

The provision of apparatus tuned in a manner as thus far described is, however, not entirely satisfactory, because the two trackway circuits mentioned preferably have currents flowing therein which are substantially in quadrature (displaced 90 electrical degrees) so as to make them distinctive, and with two influence receiving elements tuned above and below the frequency of the signaling currents, respectively, the reproduced current for operating the relay will not be correspondingly displaced (in quadrature) unless a compensating shift in the phase of these currents is made in a suitable manner. Therefore, as a further object of the present invention, it is proposed to provide means whereby the currents in the windings of the relay are caused to be shifted in the opposite direction so as to bring them into quadrature, or displace them substantially the same number of electrical degrees as are the currents flowing in the trackway circuits.

Other objects, purposes, and characteristic features of the invention will appear as the description thereof progresses.

In describing the invention in detail, reference will be made to the accompanying drawings, in which:

Figure 1 illustrates conventionally and in a diagrammatic manner the devices of the car-carried and trackway apparatus and the manner in which they cooperate;

Fig. 2 graphically illustrates the variation in phase relation of the currents in the receiving elements as compared with the in-

duced voltages for different frequencies of signaling current; and

Fig. 3 graphically illustrates the potential across and the current flowing through the condensers shunting the loop and simplex elements, respectively, for different frequencies.

Trackway equipment.—Referring to Fig. 1, there has been illustrated a trackway comprising rails 1 divided by insulating joints 2 into blocks in the usual manner. Since the various blocks are the same, the block I and the adjacent ends of blocks H and J only have been shown, and like parts of the various blocks have been assigned like reference characters with distinctive exponents. Each block is provided with a source of energy at its exit end, the normal direction of traffic being as indicated by the arrow, and comprises a transformer 3 having a secondary winding connected to the track rails in series with the usual track circuit impedance 4.

The entrance end of each block is provided with the usual alternating current track relay 5, or a track relay especially designed for systems using the train control apparatus embodying the present invention, having its local winding energized by a transformer 6. Although any one of the various well-known types of wayside signals may be used, such as color light signals, position light signals and semaphore signals, for convenience semaphore signals Z have been illustrated conventionally without illustrating their well-known circuits and control apparatus.

The loop circuit current heretofore referred to, comprising the track circuit current flowing down one rail through the axles of the train and back through the other rail, may be detected by suitable influence receiving means in front of the first axle, as more clearly explained hereinafter. In order to provide a simplex circuit current flowing down the two rails in multiple in a manner so as not to interfere with the correct performance of the track circuit and track relay, a plurality of balancing resistances are provided, to the middle points of which suitable connections are made to supply this simplex current. These balancing resistances are preferably of about 50 ohms.

Referring to the block I, the balancing resistances 7 and 8 have their middle points connected respectively to the ends of the secondary winding of the transformer 9, which has its primary winding connected to a transmission line 10. The second section of the block I may be provided with simplex current flowing in one direction or the other, depending on traffic conditions in the block J next in advance by a circuit which may be traced as follows:—beginning at the secondary winding of the transformer 6¹, wires 11¹ and 12¹, contact 13¹, wire 14, balancing resistance 15, the two track rails in multiple,

balancing resistance 16, wires 17 and 18, front contact 19¹, wires 20¹ and 21¹ back to the secondary winding of the transformer 6¹.

It should be noted that upon deenergization of the track relay 5¹, the middle section of the block I will be provided with simplex current flowing in the opposite direction through the same circuit just traced, that is, with the relative instantaneous polarity reversed by reason of the dropping of the contacts 13¹ and 19¹. The current in this event flows through wire 22 instead of wire 18.

The third and last section of the block I is provided with simplex current under clear and caution traffic conditions only of the block J by a circuit which may be traced as follows:—beginning at the secondary winding of the transformer 24, wire 25, front contact 26¹, wire 27, balancing resistance 28, the two rails in multiple, the balancing resistance 29, wire 30 back to the secondary winding of the transformer 24.

By looking at the trackway circuits illustrated in Fig. 1, it will be noted that if the block J is occupied the first section of the block I will be supplied with simplex circuit current in the same manner as under clear traffic conditions; the second section of the block I under this condition is supplied with simplex current flowing in the reverse direction; and the third section of the block I is wholly deprived of simplex current. Also, it is apparent that if a train enters a block already occupied by another train no loop circuit current, or at least an inappreciable amount, can reach the second train, because this current is shunted by the axles of the first train so that the second train is deprived of loop circuit current whereby its car-carried apparatus may be controlled, as more clearly described hereinafter.

Car apparatus.—In the particular embodiment of the invention illustrated, the car-carried apparatus includes two loop influence receiving elements LE, one located over each rail of the trackway directly ahead of the first axle of the locomotive or electrically propelled vehicle, and a simplex element SE, which is preferably located a certain distance back of the first axle 31 as shown.

Suitably mounted on the railway vehicle and protected from jar and vibration is a relay R of the two-element alternating type. Although this relay may be of the dynamometer or any other suitable alternating current two-element type, it is preferably one of that type generally known as an induction relay. The construction and operation of this induction type two-element relay, being well known and familiar to those skilled in the art, requires no specific illustration or elaborate explanation. For the purposes of this case, it is sufficient to point out that, as ordinarily constructed, such a relay has a rotor or vane as the movable element which is con-

nected to suitable contact fingers and which is biased to assume a neutral position. The contacts for such a relay R are shown conventionally in the drawings as comprising a plurality of fingers, co-operating with stationary contacts indicated by arrows, these fingers having a middle or neutral position and movable in either direction to a normal and a reverse position, respectively. This relay R also has two field coils or windings LW and SW of suitable construction. If both of these windings are energized with alternating current displaced in phase, the rotor or vane of the relay is shifted in opposition to its bias in one direction or the other. If either of these windings is deenergized, the movable element of the relay assumes its biased or neutral position. For reasons well recognized by those skilled in the art, the torque or operating force of the movable element in such a relay depends upon the product of the currents in the two field windings and also the phase displacement of these currents, the torque being a maximum for a given product of currents in the field windings when the phase displacement of these currents is 90 degrees.

This relay R has its field windings LW and SW connected to respond to loop circuit and simplex circuit currents, respectively. The loop circuit field winding LW of the relay R derives its current from suitable amplifying apparatus including thermionic amplifiers or audions LA¹ and LA² and a transformer LT; and the simplex circuit field winding SW derives its current from a similar amplifying apparatus, including the audions SA¹ and SA² and a transformer ST. Since the various circuit connections between the influence receiving element LE and the field winding LW of the relay R are substantially the same as that between the influence receiving element SE and the field winding SW, the circuits for the simplex circuit receiving element SE only will be traced; and the like parts for the loop circuit receiving element LE will be given the same reference numbers with distinctive exponents L.

The filament circuit for the audions SA¹ and SA² may be traced as follows:—beginning at the positive side of the filament battery 33, which in the particular system illustrated preferably comprises a 32 volt battery, wires 34, 35, 36 and 37, filament of the audion SA², wire 38, resistance unit 39, wire 40, filament of the audion SA¹, wire 41, resistance unit 42, wires 43, 44, 45 and 46 back to the filament battery 33. It should be noted that this circuit includes resistances 39 and 42. These resistances are used to provide the necessary negative bias of the grids of the audions SA¹ and SA² with respect to their respective filaments, so that these grids do not draw current. In the particular system disclosed good results have been obtained

by choosing resistances which cause the voltage of the grid of the audion SA¹ to be negative to the midpoint of its filament by 1½ volts; whereas the grid of the audion SA² is negative with respect to the said point of its filament to the extent of 27 volts.

The grid circuit for the audion SA¹ may be traced as follows:—beginning at the winding 48 of the simplex element SE, wire 49, resistance unit 50, wires 51 and 52, grid of the audion SA¹ to the filament of this audion, through the wire 41, resistance unit 42, wires 43, 53, 54 and 55 back to the winding 48 of the simplex element SE. The winding 48 in series with resistance unit 50 is shunted by a condenser 56 for purposes more clearly described hereinafter.

The plate circuit for the audion SA¹ may be traced as follows:—beginning at the plate battery 60, wires 61, 62, 63 and 64, primary winding of the transformer ST, wire 65, plate of the audion SA¹ to the filament of this audion, to the filament battery 33, wires 34 and 66 back to the plate battery 60.

The grid circuit for the audion SA² may be traced as follows:—beginning at the secondary winding of the transformer ST, wires 67 and 68, grid of the audion SA² to the filament of this audion, through the filament circuit and wires 69 and 70 back to the secondary winding of the transformer ST. The secondary winding of this transformer ST is shunted by a condenser 71, for the reason more clearly described hereinafter.

The plate circuit for the audion SA² may be traced as follows:—beginning at the plate battery 60, wires 61, 62, 63 and 77, inductance or choke 78, wires 79 and 80, plate of the audion SA² to the filament of this audion, through the wires 37, 36, 35 and 66 back to the plate battery 60.

The inductance 78 is shunted by a partial circuit including the winding SW of the relay R. The circuit for this winding SW which permits the flow of alternating current, due to changes of uni-directional current flow in the inductance 78, may be traced as follows:—beginning at the positive side of the plate battery 60, wires 61, 62, 63 and 77, inductance 78, wires 79 and 81, blocking condenser 82, wire 83, winding SW of the relay R, wires 84, 35 and 66 back to the plate battery 60.

In order to inform the engineer of traffic conditions ahead, suitable signals are preferably provided at a convenient point in the locomotive cab or any other suitable place, which respond to the different indicating conditions of the relay R. For simplicity, color light signals Rd, Y and G have been illustrated to indicate red (danger), yellow (caution), and green (clear), respectively. As is obvious from the circuits shown in the drawings, the green lamp G is energized when the relay R is in its normal condition

as shown, the caution lamp Y is energized when the relay is energized in the reverse direction, and the red lamp Rd is energized if the relay is deenergized.

5 Suitable apparatus is preferably provided on the railway vehicle to control the train in any suitable manner. This apparatus preferably includes a speed-responsive device and an electro-pneumatic brake control device, and suitable means for actuating the brake control device and applying the brakes of the vehicle if the speed of the train is excessive. In order to simplify the description of the present invention, a caution device Ca 15 has been illustrated to properly control the train in a caution block. This caution train control device is of the normally deenergized type, and is maintained energized under clear traffic conditions by energy flowing from one 20 terminal B of a suitable source of supply to the other terminal C of said source, as readily traced in the drawings. This device Ca is only energized when the relay R is in its normal energized condition.

25 Another control device adapted to control the train in any manner desired when moving through a danger block has been illustrated by the device Dr, as shown. This device is energized when the relay R is energized in either its normal or its reverse direction. This device preferably limits the speed of the train eventually to a predetermined low value of, say 15 miles per hour, and then maintains the speed so limited as 35 long as this device Dr is deenergized.

Operation.—Let us assume that the block J is occupied by another train, or is in a dangerous condition for some other reason, and the track relay 5¹ is deenergized. With 40 the track relay 5¹ at the entrance to the block J deenergized, the three sections from the beginning to the exit end of the block I are provided with normal simplex current, reverse simplex current, and zero simplex 45 current, respectively.

With the simplex circuit current flowing in the normal direction, that is, in a predetermined phase relation to the track circuit or loop circuit current, both field windings 50 of the relay R are energized by currents displaced in phase substantially the same as the phase displacement of the loop and simplex circuit currents, and consequently the movable element of the relay assumes its normal 55 position shown, lighting the green lamp G and energizing both the caution control device Ca and the danger control device Dr. In other words, with the relay R in its normal 60 position, a clear or proceed cab signal is displayed and the speed restrictions or other control enforced by the danger and caution control devices are not in effect. The speed of the train under such clear traffic conditions may be unlimited, or if desired, this normal 65 running speed may be limited to some arbit-

rary maximum, such as 65 miles per hour. The relay R is maintained in the normal condition, with the results just noted, while the train is traveling through the block H under the clear traffic conditions assumed to exist. 70

As the train moves into the block I, the block J next in advance being assumed to be occupied, there is no change in the position of the relay R during the travel of the train over the first section of this block I between the balancing resistances 7 and 8, for the reason that the simplex circuit current is still of the normal relative polarity or phase relation. This particular arrangement has been selected to illustrate how the caution control may be made effective at some selected point beyond the caution signal itself, or the actual entrance to the caution block, this condition existing more particularly in the case of long blocks that are longer than the braking distance necessary; but it should be understood that the balancing resistances 7 and 8, together with transformer 9, may be omitted, and the balancing resistance 15 located at the joints 2 marking the entrance 80 to the caution block. 85

As the train moves beyond the balancing resistance 15, the relation between the loop and simplex circuit current detected by the car-carried apparatus is reversed; and the relay R changes to shift its contact fingers to the reverse position, thereby deenergizing the caution train control device Ca but maintaining the danger control device Dr energized. Also, the green lamp G is extinguished and the yellow lamp Y is lighted. The engineer will, therefore, be required to reduce or govern the speed of the train in accordance with the permissive speed set up by the caution speed device Ca. In one arrangement, the action of the caution speed device compels reduction in speed to an intermediate speed of, say, 40 miles per hour. 100

As the train passes the point D, it is entirely deprived of simplex circuit current and the relay R is deenergized, its field winding SW having no current therein. The engineer is now required to govern his speed in accordance with the requirements of the danger train control device Dr or there is an automatic application of the brakes. The danger control device is made effective at the point D and before the end of the block I is reached, in order to assure that the train reaches a predetermined safe low speed (say 115 15 M. P. H.) or comes to a stop before reaching the end of the block. 120

As the train proceeds into the block J, this block still being occupied by said another train, the relay R is maintained deenergized regardless of simplex current flowing in the simplex circuit of the block J. This is true because no loop circuit current, or at least not an appreciable amount, will be flowing, so that the relay R is deenergized primarily 130

on account of the lack of current flowing in the winding LW of the relay R. Consequently, the restriction in the movement of the train is continued so that it can not exceed 5 said minimum speed limit until the said another train leaves the block J. As soon as this occurs the train in question is no longer restricted to this low limiting speed unless the train has passed the point D of the block J. 10 Net, since the present system is based on the principle of continuous control, or a permanent communicating link between the train and track relays ahead, the train will be immediately released and permitted to proceed 15 as soon as traffic conditions ahead become more favorable, all in the manner well known by those familiar with this type of continuous inductive train control system.

Constants of elements of the various car-carrying devices.—In order to obtain the desired performance of the car-carried apparatus under varying frequencies, a varying amount of current flowing in the simplex and loop circuits, respectively, reasonable variation 20 in the phase displacement between these two currents and other varying conditions encountered in practice, the various circuit portions of the car-carried circuits are tuned and adjusted in a predetermined manner to 25 be presently described. The variation in the frequency of the alternating signaling current to be picked up and amplified exists and must be compensated for, because this current will in practice be derived from a 30 transmission line supplied with current from commercial apparatus and will have the small frequency variations ordinarily found in commercial power sources. The amount of current in the loop or track circuit varies in 35 accordance with the location of the train in the block, being a maximum with the train at the exit or feed end of the block and a minimum at the entrance end of the block. Variation 40 in the phase relation of the currents in the trackway loop and simplex circuits is occasioned by the different electrical characteristics of the blocks, due to changes in ballast resistance, location of the train in the 45 block, and other factors.

50 As previously stated, it is desirable to tune more or less sharply the coils of the receiving elements so as to obtain the maximum voltage for application to the grids of the vacuum tube amplifiers for the minimum amount of 55 signaling current in the track rails. Roughly speaking, it has been found that, by the arrangement shown and hereinafter explained, the tuning of the coils of the receiving elements serves to give an input voltage 60 for the vacuum tube amplifiers which is from 6 to 10 times the voltage induced in these coils. Such voltage increase or manifestation is characteristic of voltage resonance and is 65 very desirable in train control systems of this type. Hence, a condenser, such as 56, is con-

nected in series with the coil, as 48, of each receiving element.

With such an arrangement, it is evident that there is a particular frequency for which the combination is resonated and the voltage 70 across the condenser is a maximum; and it is equally evident that for other frequencies the voltage will be lower. Similarly, for the particular frequency for which the receiving coil is tuned, the induced voltage and current in this coil are in phase with each other and have a definite phase relation to the current in the track rails producing such voltage and current; whereas for a different frequency, 75 the current in the coil of the receiving element and the voltage across the condenser (which is the potential applied to the amplifier) does not have the same definite phase relation to the inducing current in the track-way circuit, due to the fact that for such different frequency there is more inductive reactance in the tuned circuit than condensive reactance, or vice versa. Consequently, if 80 the receiving coils are tuned sharply to resonate at a predetermined frequency, such as 85 60 cycles, any variation in this frequency gives not only a lower voltage to be applied to the grid of the first amplifying tube, but also shifts the phase relation with respect to the current in the track rails. These effects, 90 more particularly the change in voltage, act to change the torque of the relay R; but it is desirable, however, to have substantially the same torque for the relay R under the variations and frequencies to be encountered in 95 practice. It may be said that the present invention deals principally with the problem of arranging or adjusting the circuits and devices on the locomotive or other vehicle, so as to 100 attain substantially uniform torque for the 105 relay under the varying conditions of frequency encountered in practice.

For the purpose of explaining the nature and underlying principle of this invention, it is assumed that the normal signaling frequency is 60 cycles, and that compensation should be made for a variation of 2 cycles either way. In other words, in this explanation, it is assumed that the equipment is designed to give a substantially uniform torque 110 for the relay R for a range of frequencies between 58 and 62 cycles per second, it being understood of course that this is merely illustrative.

As a further aid in explaining this invention, certain curves or graphs have been shown in Figs. 2 and 3, these being drawn on the basis of certain assumed conditions which are of course susceptible of considerable variation in practice. Fig. 2 illustrates 120 the phase relation of the current in the coils of the loop and simplex circuit elements with respect to the voltage induced in these respective coils for different frequencies. The horizontal distances or abscissa represent fre- 125 130

quencies, and the vertical distances or ordinates denote phase angle, positive phase angles or leading current being on the upper half of the figure above the horizontal line, and a negative phase angle or lagging current below said line.

Fig. 3 illustrates in two separate groups of curves to different ordinates, the variation in the current in the coils and also in the tuning condenser of the loop and simplex circuit elements, as the frequency varies, and also the voltage across the tuning condenser for said elements.

As previously stated, the torque of the relay R depends upon the product of the currents in its respective field windings. Assuming proportionate amplification throughout the working range of voltages, the currents in the field windings of the relay are proportional to the voltages impressed upon the input circuits of their respective amplifiers. In other words, as the voltage across the condenser 56 for the simplex circuit receiving element SE increases or decreases, it may be assumed that the current in the field windings SW of the relay R correspondingly increases or decreases. It has been pointed out, however, that this voltage changes with the frequency, and hence the current in said field winding likewise varies. Thus, if both of the receiving elements are tuned by their respective condensers to resonance for the same frequency, an increase or decrease in this frequency would result in a diminution of the current in both field windings of the relay and result in a lower torque. It is this condition that the particular arrangement of this invention, among other things, is proposed to remedy.

Generally stated, according to this invention, the condenser 56 in series with the coil 48 of the simplex circuit receiving element SE for tuning this coil, is preferably chosen, or adjusted, to a capacity approximately 20% more than that required to produce resonance for the normal frequency of 60 cycles; and similarly, the condenser 56^L is adjusted with about 20% less capacity than required to produce resonance for said normal frequency. In other words, the coils of the two receiving elements are tuned, not to the same frequency, but to different frequencies. More specifically, on the basis of the assumptions hereinbefore mentioned, for a range of frequencies from 58 to 62 cycles, one satisfactory arrangement is to tune the coil of the simplex element SE for resonance at about 54½ cycles and the coil of the loop circuit element LE for resonance at about 65½ cycles. This particular arrangement has been indicated in the illustrative curves, as apparent from Fig. 2, the points of resonance being shown for the frequency producing zero phase displacement.

Assuming now that the coils of the two

receiving elements are tuned off resonance for the normal signaling frequency, as just stated, and referring to Fig. 2, it will be seen that the induced current and likewise the voltage across the tuning condenser is not the maximum for the normal frequency of 60 cycles but is an intermediate value. Referring particularly to the voltage curves in Fig. 3, it will be noted that these curves have substantially the same general form and slope, especially over the range of frequencies for which the equipment is designed, namely, between 58 and 62 cycles. It will also be noted that, as the normal frequency of 60 cycles is increased, for example, to 62 cycles, the voltage across the condenser 56 for the simplex element SE decreases, while the voltage across the condenser 56^L for the loop circuit receiving element LE increases; and on account of the similarity in this variation, the product of the voltage remains practically constant throughout the band of frequencies in question. For example, at 58 cycles the voltages are 2.2 and 2.4 with a product of 5.2; at a frequency of 60 cycles, the voltages are 1.7 and 2.9 with a product of 4.93; and at 62 cycles, the voltages are 1.3 and 3.7 with a product of 4.81. In short, the products of the voltages or potentials impressed on the amplifiers remain substantially constant, one increasing as the other decreases with a change in frequency, and vice versa, so that the currents in the field windings of the relay R change, one increasing and the other decreasing, with a change of frequencies, their products remaining substantially constant and the torque nearly uniform.

The arrangement just described for maintaining uniform relay torque for different frequencies, consisting of tuning the receiving elements to higher and lower frequencies respectively than the normal frequency, serves admirably for this particular purpose, but introduces additional factors and considerations. Mention has been made of the fact that the phase relation of the induced currents in the coils of the receiving elements varies with respect to the induced voltage as the frequency varies. If such variation in phase relation were truthfully reproduced proportionally throughout the amplifiers and up to the field windings of the relay R, the net effect upon the relay would be substantially the same, the currents in its field windings both becoming more leading or lagging, as the case may be, and to the same degree. Exact similarity and faithful reproduction of phase relation throughout an amplifier arrangement, particularly with apparatus built in quantity on a commercial basis, is not easy to obtain or maintain, with the result that compensating adjustments are desirable and almost essential.

Another desirable attribute of the car

equipment for a system of the character under consideration is that there should be no ultimate change in phase relation produced by the car apparatus by itself, that is, the 5 phase relation of the currents in the windings of the relay R should be the same as the phase relation between the currents in the simplex and loop circuits. This is desirable for several reasons, and more particularly to avoid 10 the possibility of false operation under peculiar conditions. To illustrate, suppose that the balancing resistance 16, for example, should have its connection to one of the track rails broken. This would cause all of the 15 simplex circuit current to flow in the other rail and pass under one of the loop circuit receivers LE. Such current would induce a corresponding voltage in the coils of the receivers LE and apply it to the grid of the vacuum tube LA¹, the current being confined to 20 one rail so that there could be no balancing effect due to the way in which these coils are wound. If the existence of such abnormal simplex current and its action upon the 25 amplifier for the loop circuit produces upon the winding LW of the relay R the same effect as the regular or authorized loop circuit, then false operation of the relay might occur, that is, the relay might be energized directly 30 behind a train in the same block which would shunt out the loop circuit current but would not change the flow of the false simplex current all in one rail. As a remedy for this 35 possibility, it is proposed to arrange the loop and simplex circuit receiving elements and their amplifiers so as to have inherently no phase displacement and produce all of the phase displacement, necessary for operation of the relay R, in the trackway circuits. With 40 such an arrangement, false application of the simplex circuit to the loop circuit receiving elements could not produce any improper effect upon the relay, since this current would be in phase with the regular simplex circuit 45 current in the other winding of the relay, and this relay, as already explained, requires a phase displacement in the currents in its field windings in order to operate.

Generalizing, it is desirable, for the reasons indicated, and others not requiring specific discussion, to provide an organization of circuits for receiving loop circuit current, and also for receiving simplex circuit current, which produces no phase shift on the car. 55 In order, however, to maintain substantially uniform torque on the relay, the coils for the simplex and loop circuit elements have already, as previously explained, been tuned off resonance for the signaling frequencies, so 60 to speak, with the result that at the signaling frequency one is lagging and the other is leading with respect to the currents in the track rails producing such currents.

This condition just discussed is best explained by referring to Fig. 2, from which it

can be seen that, with the tuning as indicated in Fig. 3 and as already explained, the alternating current in the coil of the loop circuit element, on account of the smaller value of the condenser, leads its induced voltage by 70 about 48 degrees at the normal frequency of 60 cycles, whereas the current in the coil of the simplex receiving element lags behind its inducing voltage by about 59 degrees. In 75 order to bring the currents applied to the windings of the relay R back into phase, it is necessary to make a similar compensation in another part of the operative chain between the receiving coil and the relay windings, more specifically in the amplifier. This 80 is accomplished by using an inductive or reactive coupling between the first and second stages of the amplifier, namely, a transformer ST or LT, and tuning these in an opposite fashion by a condenser 71 or 71^L. 85

To illustrate, assuming the condenser 56^L adjusted to resonate the coils of the loop circuit receivers for a frequency higher than the normal frequency and the condenser 56 adjusted to tune the coil of the simplex receiver for a frequency lower than the normal frequency, then the condensers 71 and 71^L can be selected or adjusted in either of two ways to produce the desired compensation. According to the first method, the condenser 71^L 95 is selected to make the current derived from the first amplifier LA¹ of the loop circuit device still more leading, and the condenser 71 to give a still more lagging current, so as to bring about a phase difference of 180 degrees. 100 According to the other method, which is considered to be preferable, the condensers 71 and 71^L are selected or adjusted to bring the currents back into phase, that is, with the current in the loop circuit chain of devices leading 105 as shown in Fig. 2, the condenser 71^L is adjusted to give a compensating lag. It is, of course, evident that if the condenser 56^L gives a lead of 48 degrees, the condenser 71^L need not necessarily give a lag of the same angle, 110 so long as the condensers 71 and 71^L together compensate for the total phase angle difference. In other words, assuming the condenser 56^L gives a lead of 48 degrees, as shown 115 in Fig. 2, the condenser 71^L may be adjusted to give a lag of, say, 58 degrees, instead of 48 degrees, or a 10 degree over-compensation, but in that case the condenser 71 would be adjusted to give a lead of 10 degrees less, or 48 degrees, instead of 58 degrees, according to 120 the values assumed and shown in Fig. 2.

The transformers ST and LT have been referred to as used for the purpose of obtaining a compensation in the amplifiers to bring about zero degree phase displacement; but 125 it should be understood that these transformers have other advantageous characteristics. For example, these transformers introduce an additional tuned element in the operative chain of devices between the currents in the 130

trackway circuits and the windings of the car relay; and consequently these transformers give greater selectivity and render the whole system less susceptible to operation by currents of frequencies widely different from the normal signaling frequency. It may be said that this feature of selectivity is desirable more particularly in the case of railroads employing alternating current for propulsion purposes. Likewise, such selectivity is desirable to render the relay immune to improper operation by stray currents of odd frequencies.

It will be readily recognized that the use of transformers LT and ST introduces the same problem of maintaining a uniform torque for the relay as the frequency varies, as in the case of the coils of the receiving elements themselves, but this difficulty is taken care of by reason of the fact that these transformers are tuned off resonance in the same way and with the same effect as described in connection with the coils of the receiving elements. The curves or graphs in the case of the transformers, being similar to those shown in Figs. 2 and 3, have not been illustrated; and in view of the foregoing explanation it is thought to be unnecessary to discuss this scheme of selection or adjustment of the constants for these transformers.

The desired phase displacement of the currents in the simplex and loop circuits on the trackway may be obtained in accordance with any one of the well-known expedients employed in connection with alternating current track circuits. According to the arrangement illustrated, which is preferable for ordinary conditions, the simplex circuit is made resistive, so that the current therein is substantially in phase with the transmission line voltage; whereas the loop circuit is made reactive, so that the current therein lags behind the transmission line voltage. For this reason, the reactance 4 is introduced in series with the secondary of the transformer 3, this reactance serving the purpose of the usual limiting reactance or resistance employed to limit the flow of current as a train approaches and stands directly over the feed end of the track circuit.

It may be explained here that the invention has been shown in connection with alternating current track circuits, but the same principles are applicable to direct current track circuits, the alternating current used for train control purposes being superimposed upon the direct current, as for example, by connecting the transformer feed in series with the track battery.

As previously stated, it is considered to be desirable in systems of this character to have no phase shifting by the car apparatus, and have the phase displacement of the currents in the field windings of the relay correspond with the phase displacement of the currents

flowing in the simplex circuits on the trackway. Based on this premise, the car apparatus may be readily adjusted to function in the desired manner in the following fashion. First, the coils of the receiving elements are tuned off resonance to frequencies higher and lower than the normal frequency. Then with these receiving elements energized by currents exactly in phase, the condensers 71 and 71^L are adjusted so that there is no torque produced by the relay. These adjustments, it may be added, are preferably made after trial with variations in frequency and strength of current in the trackway circuits, such as would be encountered in practice. After obtaining an adjustment of the car apparatus in this manner, the currents in the trackway and loop circuits are thrown out of phase through angles corresponding to that likely to be encountered in practice, these currents respectively reversed and cut off, and the torque of the relay R noted.

Mention has been made of the fact that there is considerable variation in the amount of loop circuit current influencing the receiving elements LE as the train travels through a block. So long as the car equipment is sufficiently sensitive to produce reliable operation of the car relay with the minimum amount of loop circuit current, existing when the train first enters a block, the additional energization of the relay by the increase of loop circuit current is not particularly objectionable; but it may be explained that this condition is under control and may be duly compensated for by reason of the saturation or overload characteristics of the vacuum tube amplifier. In other words, the amplifiers for the loop circuit particularly may be worked at such a point that excessive loop circuit current does not produce excessive relay current.

The condensers 82 and 82^L, in series with the field windings of the relay R, are provided primarily to prevent the direct current from the plate battery 60 flowing through these windings, and these condensers are essentially blocking condensers. These blocking condensers 82 and 82^L of course reduce the impedance of the circuits including the field windings of the relay by compensating for the reactive component; and in practice these condensers are preferably of the value to produce resonance for the normal frequency, that is, the condensive reactance of these condensers is made equal to the inductive reactance of the field windings of the relay. The tuning of the field windings of the relay, however, does not produce very sharp resonance because there is included in the tuning circuit the high internal resistance of the vacuum tube amplifier. In other words, the field windings of the relay do not have a sharp or peaked resonant curve and respond much the same over the range of frequencies applied thereto.

This well known fact that resistance in the tuning circuit flattens or broadens the resonance curve may also be utilized in connection with the receiving elements; and it is found desirable in many instances to include in series with these elements a resistance unit 50 which may be selected or adjusted to give a more flexible control over the constants of these two circuits and promote stability of 10 the system.

Summarizing the features of this invention, it will be observed that the system of train control of the continuous inductive type employs two separate trackway circuits, being conveniently termed the loop and simplex circuits. The currents in these circuits are derived from a transmission line of commercial characteristics with the usual frequency variations, and these currents are displaced in 20 phase by any one of the well known expedients and are individually controlled in the specific manner described to give three distinctive controlling conditions, namely, simplex circuit current normal, simplex circuit 25 current reversed, and simplex circuit or loop circuit current cut off. Uniform torque for the car relay is maintained by adjusting the receiving elements to frequencies higher and lower than the normal frequency; or, in other 30 words, these receiving elements are tuned off resonance. These tuning conditions are selected to give a substantially uniform product of the voltages impressed upon the amplifiers throughout the range of frequency variation 35 to be encountered.

In order to have the desired feature of zero degree phase displacement by the car apparatus, an additional reactive device (coupling transformers) is introduced in each 40 operative chain between the receiving elements and relay, and this additional device is tuned off resonance to give a constant product of voltage and uniform relay torque and also so as to compensate for the phase change 45 produced by the tuning of the receiving elements. In a sense, it may be said that each of the chain of devices for the loop and simplex circuits has one link thereof (the receiving coil) tuned to resonance for a frequency considerably but oppositely different from the signaling 50 frequency, and another link (coupling transformer) tuned for a frequency also considerably but oppositely different from the signaling frequency. These tunings are such that 55 the ultimate result is proper operation of the relay in producing substantially uniform torque for a range of frequencies, say from 58 to 62 cycles, without sacrificing the efficiency and advantages of tuned circuits and 60 without departing from the safety principle of having car apparatus operable only by trackway currents which are displaced in phase.

The present invention provides, therefore, 65 a system for transmitting inductively any one

of three distinctive control influences to a vehicle at any and all points in its travel, with due allowance and compensation to meet the conditions actually encountered in practice, more particularly variations in frequency, and without sacrificing the advantages of tuned circuits. It should be understood that the specific organization of devices and circuits herein shown and described is merely illustrative of the invention, and that the invention is not limited to this specific embodiment. For example, while a polyphase relay of the inductance type has been assumed, relays of the dynamometer or other type may be used, the system applied to direct current 80 track circuits, and various adaptations and modifications made in other respects, all without departing from the invention.

What we claim is:—

1. In an automatic train control system, 85 the combination or trackway means for transmitting currents in two distinct trackway circuits, one of which consists of the usual track circuit; and car-carried apparatus including influence receiving elements having windings located in inductive relation with said trackway circuits, condensers connected in multiple with said windings having capacities to tune these windings to higher and lower frequencies respectively than the proposed signaling frequency, a two-element electro-responsive device operated in response to currents flowing in the windings of said elements, and train control means governed by said electro-responsive device. 90

2. In an automatic train control system, 105 the combination of trackway means for transmitting currents in two distinct trackway circuits, one of which consists of the usual track circuit; and car-carried apparatus including influence receiving elements having windings located in inductive relation with said trackway circuits, condensers connected in multiple with said windings having capacities to tune these windings to higher and lower frequencies respectively than the proposed signaling frequency, two amplifying devices having their input circuits connected to the terminals of said condensers, a two-element relay having its windings connected to the 110 output circuits of said amplifying devices, and train control apparatus governed by said relay. 115

3. In an automatic train control system, 120 the combination of trackway means for transmitting currents in two distinct trackway circuits, one of which consists of the usual track circuit; and car-carried apparatus including influence receiving elements having windings located in inductive relation with said trackway circuits, condensers connected in multiple with said windings having capacities to tune these windings to higher and lower frequencies respectively than the proposed signaling frequency, two amplifying 125 devices having their input circuits connected to the terminals of said condensers, a two-element relay having its windings connected to the output circuits of said amplifying devices, and train control apparatus governed by said relay. 130

devices connected to respond to the potentials across said condensers having inductive output circuits, a polyphase relay having its windings connected to said output circuits, and means for tuning said output circuits so as to cause the phase displacement between the currents flowing in the two windings of the relay to be substantially the same as the phase displacement of the currents flowing in the trackway circuits.

4. In an automatic train control system, the combination of trackway means for transmitting currents in two distinct trackway circuits, one of which consists of the usual track circuit; and car-carried apparatus including influence receiving elements having windings located in inductive relation with said trackway circuits, condensers connected in multiple with said windings having capacities to tune these windings to higher and lower frequencies respectively than the proposed signaling frequency, two amplifying devices having their output circuits connected to transformers, a polyphase relay operated in response to the potentials across the output terminals of said transformers, and means associated with said transformers for causing the potentials across the output terminals of said transformers to be displaced substantially the same amount as are the currents flowing in said trackway circuits.

5. Car-carried apparatus for automatic train control systems of the type in which two distinctive trackway currents are transmitted along the trackway, one of which flows in the usual track circuit ahead of the train comprising, a two-element alternating current relay each element having a winding, two inductive influence receiving elements located in inductive relation with said trackway circuits, two chains of circuits and devices connecting said receiving elements and the windings of said relay, certain of the elements of said chains being resonated to frequencies different from the frequency of the proposed trackway currents.

6. Car-carried apparatus for automatic train control systems of the type in which two distinctive trackway currents are transmitted along the trackway, one of which flows in the usual track circuit ahead of the train comprising, a two-element alternating current relay each element having a winding, two inductive influence receiving elements located in inductive relation with said trackway circuits, two chains of circuits and devices connecting said receiving elements and the windings of said relay, certain elements of each chain being resonated to different frequencies both above and below the proposed frequency of said trackway currents, and the corresponding elements of the two chains being resonated to frequencies above and below, respectively, the proposed frequency of said trackway currents.

7. Car-carried apparatus for automatic train control systems of the type in which two distinctive trackway currents are transmitted along the trackway, one of which currents flows in the usual track circuit ahead of the train comprising; a two-element alternating current relay each element having a winding; two inductive influence receiving elements located in inductive relation with said trackway circuits; two chains of circuits and devices connecting said receiving elements to the windings of said relay; each of said chains including, two audions having their filaments connected in series, and a resistance unit in the circuit of said filaments contained between said filaments and having an ohmic resistance of a value so that the filament current flowing therethrough will produce the proper grid bias in one of said audions with respect to the grid bias of the other audion.

8. In an automatic train control system, the combination with separate trackway circuits including track rails and energized subject to control in accordance with traffic conditions by alternating currents of the same frequency but different in phase, a two-element alternating current relay on a vehicle, and means on the vehicle inductively influenced by the alternating currents in said trackway circuits for amplifying the energy manifestations produced by such currents and applying the energy so amplified to said relay without phase distortion and giving a substantially uniform torque for the relay for all frequencies throughout a predetermined range.

9. In a continuous inductive impulse communicating means for train control purposes, the combination with a two-element alternating current relay on a vehicle, of receiving coils and amplifiers supplying current to the field windings of said relay, and means tuning said receiving coils and amplifiers to provide a substantially constant product of the currents in the field windings of said relay for all frequencies throughout a predetermined range.

10. In a train control system of the character described including track rails normally having alternating signaling current flowing therein, separate receiving elements having coils and condensers tuning said coils, one to a lower and the other to a higher frequency than the normal signaling frequency.

11. In a train control system, the combination with trackway circuits energized with alternating current differing in frequency from a normal throughout a range of frequencies, of a car-carried two-element alternating current relay, and amplifying means detecting the flow of alternating current in said trackway circuits and supplying current to the field windings of said relay, said currents in said field windings having the

same phase displacement as the currents in the trackway circuits and having a substantially constant product for all frequencies throughout said range.

5 12. A system for continuously and inductively communicating anyone of a plurality of control influences of a distinctive character to a moving vehicle by causing operation of a two-element alternating current relay, 10 characterized by the provision of means for producing a substantially constant torque in the moving element of said relay throughout a predetermined range of frequencies.

13. In an automatic train control system 15 of the character described, in which the operation of a two-element alternating current relay on a vehicle is controlled by the presence and absence and also relative phase relation of alternating currents in two trackway circuits, the provision of means for maintaining 20 a substantially uniform torque for said relay throughout a predetermined range of frequency variation.

14. Car-carried apparatus for automatic

train control systems of the type in which two distinctive trackway currents are transmitted along the trackway, one of which flows in the usual track circuit ahead of the train comprising; a two-element alternating current relay each element having a winding; two inductive influence receiving elements located in inductive relation with said trackway circuits; two chains of circuits and devices connecting said receiving elements to the windings of said relay; each of said chains including, an audion having its plate circuit divided into two branches in multiple one of which includes an inductive reactance and the other of which includes a winding of said relay and a condenser in series, whereby the direct current component of the plate circuit current does not flow through the winding of said relay.

In testimony whereof we hereby affix our signatures.
